10 Claims. (Cl. 93—36.5)

In the manufacture of containers made of sheet material such as paper or cardboard, which may be previously coated or not, it is usual for the free edge of the container to be rolled, thereby ensuring smoother pouring of the contents, and, in cases where the contents are absorbed straight from the container, a more agreeable sensation for the lips.

In most devices used for forming rolled edges, the sheet material used for the container penetrates into a fixed rolling groove which restrains the material over the outer surface of the rolled edge.

Whereas such rolled edges can readily be formed with conventional apparatus when the diameter of the opening in the container to be provided therewith is relatively large, the operation becomes far more delicate when the diameter referred to is relatively small, and particularly when frusto-conical containers with open smaller bases are involved. Due to the restraining action to which the rolled edge is submitted on its external surface during the rolling operation, the sheet material used for the container is subjected to considerable stresses owing to the fact that the rolling diameter of the rolled edge represents a relatively large fraction of the diameter of the opening. This results in tears or cracks in the sheet material, which are all the more detrimental in that the latter is previously coated with a protective lining. Furthermore, it is impossible to hot-roll an edge when polyethylene (hereinafter called "polythene") is used, although this is customary procedure with ordinary cardboard.

The main object of the present invention is to overcome these drawbacks and to provide fully cold-rolled edges in a single operation. For this purpose, the present invention provides an apparatus for forming rolled edges on containers made of sheet material, comprising, on the one hand, rolling means consisting of a central part having thereon an external circular throat of quarter-circle section and of jaws mounted under light friction on the support of said central part, which are radially slidable behind the same and have formed on their inner faces an arcuate groove of semi-circular cross-section that jointly form with said throat a hollow toroidal rolling die, and, on the other hand, means for axially moving said rolling means toward the container mounted on a fixed coaxial support whereby to roll down its edge in said die, means for opening said jaws after formation of the rolled edge and means for closing them anew after said rolling means recede from the container formed with its rolled edge.

Thus, as the rolling means move toward the container and the sheet material forming the latter is rolled back in the rolling die, and as the rolling diameter gradually increases, said jaws are displaced by sliding radially against their restraining friction and thereby no longer clamp the material formed into a rolled edge.

The description which follows with reference to the accompanying non-limitative exemplary drawings will give a clear understanding of how the invention can be carried into practice.

In the drawings:

FIG. 1 shows in axial section the apparatus for forming the rolled edges according to the invention in the inoperative position.

FIG. 2 is a fragmental view corresponding to FIG. 1, showing the rolled edge being formed.

2

FIG. 3 is a fragmental view similar to FIG. 1, after completion of the rolled edge, when the latter is about to be disengaged from the apparatus.

FIG. 4 is a fragmental view similar to FIG. 1, after completion of the rolled edge and the reverting of the apparatus to the inoperative position.

FIG. 5 is a view of the jaw-bearing web looking in the direction of the arrow F of FIG. 4, showing the three component parts of a jaw positioned differently for illustrative purposes; and

FIG. 6 is a partial diametrical section, on an enlarged scale, through a container with a finished rolled edge.

The purpose of the apparatus shown in the accompanying drawings is to form a rolled edge on the opening 1 of a frusto-conical container 2 open over its smaller base. This container is mounted in a fixed support 3 and centered thereon by a hollow frusto-conical part 4. The larger base of the container bears on a surface 5 consisting, say, of the thrust face of a tool used to complete the fitting of the container bottom.

The means for forming the rolled edge include a hollow tool-carrier 6 coaxial with the part 4 and fixed through a base 7 to a fixed support 8. Through the medium of screws 9, the carrier 6 supports a bell-mouth 10 along the lip of which is formed an internal chamfer 11.

Within the tool-carrier 6 is fitted a hollow slidable part 12 forming the tool shank and terminating in a jaw-bearing web 13. Within the tool shank 12 is mounted an arbor one end of which is formed as a cam with six inclined facets 16 acting as a multiple wedge. Against these inclined facets 16 bear angularly-shaped slides 17 having an apex angle of 60° and terminating at their outer ends in chamfers 14 which, in the inoperative position, engage with the chamfer 11 on the bell-mouth 10. Each slide is retained on the jaw-bearer 13 by a screw 20, a spring 21 being interposed between the head of this screw and a washer 22 bearing against the rear face of the web 13. Each screw extends through an oblong opening 23 formed in the web 13, thereby acting as guide means for the corresponding slide 17.

Secured to each slide 17 by a screw 24 is a part 25 for restraining the associated jaw, which part is centered on the corresponding slide 17 by an arcuate tenon 26 cooperating with a mortise 27 formed in that slide. Between each slide 17 and each restraining part 25 is mounted a jaw 28 made of anti-friction material, set into a lodging 29 in the slide and formed with an arcuate rib 30 engaging in a matching groove in the part 25. The assembly consisting of each part 25 and the corresponding jaw 28 and slide 17 thus forms a whole capable of moving radially over the jaw-bearing web 13.

Each jaw terminates adjacent the center in a flat portion 31 which is in contact with the larger base of a frusto-conical part 32 in anti-friction material centered on the main axis of the apparatus and provided with a cylindrical base 58 for centering the jaws. This part 32 is spring-loaded against the jaws 31 and the slides 17 by a screw 33 which is carried by the arbor 15 and beneath the head of which is disposed a spring 34 pressing a thrust washer 35 against the smaller base of frusto-conical part 32. Adjacent its larger base this frusto-conical part has formed thereon a toroidal throat 36 having a quarter-circle section which is extended over the jaws, in the inoperative position, by an arcuate groove 37 of semi-circular section the front edge of which is spaced from the external conical surface of the part 32. The throat 36 and the groove 37 jointly form a rolling die.

At its end remote from its web 13, the tool shank 12 terminates in a cylindrical recess 38 and in an external screw thread 39 onto which are screwed a nut 40 and a locknut 41. The arbor 15 terminates in a section of smaller diameter 42 having thereon a terminal screw

thread 43 onto which are screwed two nuts 44 and 45 which clamp between them a part 46 provided with an upper lug 47 and a lower arm 48. Fitted over the section 42 of the arbor 15, between the bottom of the recess 38 and the nut 44, is a spring 49 which urges the arbor 15 away from the tool shank 12 and the jaws until a pin 6a rigid with the shank butts against the front end of an opening 15a extending through the arbor 15. A second spring 50 of lesser strength than the spring 49 connects the lug 47 to a fixed point 51 and biases the tool assembly rearwardly. On the lever 48 is pivotally mounted a link 52 the other end of which is pivotally connected to a lever 53 fulcrumed about a fixed shaft 54. The lever 53 carries a follower 55 urged by the spring 50 against a cam 56 mounted on the apparatus actuating shaft 57.

The apparatus hereinbefore described operates in the following manner:

Referring to the configuration of FIG. 1, in which the container 2 has been mounted in its support 4 with its bottom pressing against the fixed surface 5, when the drive shaft 57 is set in operation, the part 46, in response to the cam 56, exerts a thrust against the bottom of the recess 38 through the agency of the spring 49. This spring is sufficiently strong to transmit without being compressed the force required to roll down the edge of the container and allow the apparatus to adopt the configuration of FIG. 2, in which the nut 40 butts against the tool-carrier 6.

In the course of this motion, the tool shank 12 will have moved together with the arbor 15 through the tool-carrier 6, thereby causing the edge-rolling means to project from the fixed bell-mouth 10. The container edge 1 is guided by the outer surface of the frusto-conical part 32 and caused to penetrate into the rolling die formed by the throat 36 and the grooves 37. Subsequently, as the edge-rolling means move toward the container, the edge is rolled back onto itself in said die, with the throat 36 fulfilling a prerolling function. As the rolling diameter increases, the material used for the container moves externally the jaws 28 against the counteracting friction exerted by the washers 22 responsively to the springs 21, as shown in FIG. 2. The rolled edge is thus formed without any constraint being applied to it by the jaws which, by virtue of their radial shift, provide a slight clearance between their faces and the cylindrical base 58 of the frusto-conical part 32, between the bearing faces of the slides 17 and the inclined facets 16, and between the ends of the oblong openings 23 and the screws 20.

As the cam 56 continues to rotate, the spring 49 is compressed by the nut 44, causing the arbor 15 to be moved. Through its terminal inclined facets 16, the arbor 15 causes the compound consisting of the slides 17, the jaws 28 and their restraining parts 25 to recede radially, said compound being guided by the screws 20 sliding through the openings 23. This radial recession is effected over a distance such that the front edges of the arcuate grooves 37 of semi-circular section move back sufficiently to permit the rolled edge 59 to be disengaged from the rolling means (see FIG. 3). Said compound is restrained in the withdrawn or open position by reason of the friction of the washers 22 loaded by the springs 21.

As the cam 56 rotates further, the compound is returned to the position of FIG. 4 responsively to the reaction of the spring 50, the spring 49 having meanwhile caused the arbor 16 to withdraw through the tool shank 6 until the pin 6a contacts the forward edge of the opening 15a. The internal chamfer 11 on the bell-mouth 10 simultaneously fetches the jaws into their closed inoperative position by coacting with the external chamfers 14 on the slides 17.

During the advance and withdrawal of the multiple wedge, the frusto-conical part 32 is held centered by the friction which is exerted on it by the plate 35 responsively to the spring 34.

Preferably, the jaws 28 and the frusto-conical part 32 are made of a synthetic resin of the polytetrafluoroethylene class, an example being the resin known by the trade name "Teflon."

5 There is thereby obtained a rolled edge free from creases, tears or cracks if the sheet material used for the container is provided with a lining such as a thermoplastic lining and most notably a polythene lining, thereby giving the container a most pleasing appearance.

10 Preferably, the seal down the side of the sheet material forming the container is made in the manner described in the U.S. Patent Application Serial No. 428,295 filed this day by the Applicant and entitled "Method and Apparatus for Leaktightly Joining Materials in Sheet Form," in

15 order that the jaw facing this seal should not be displaced to an unduly large extent relatively to the displacement of the other jaws and thereby detract from the appearance of the rolled-down edge.

The apparatus according to the present invention can 20 be used for forming rolled edges on frusto-conical containers and cylindrical containers alike. In the case of frusto-conical containers having their larger base open, the apparatus is supplemented by means for restraining the container internally against its fixed support.

25 What I claim is:

1. An apparatus for forming a rolled edge on a container in sheet material having a shape of revolution and mounted on a fixed support, comprising, in combination, a central part which is centered on the axis of the container mounted on its fixed support and which has formed thereon rearwardly of its perimeter an arcuate throat of quarter-circle section at a distance from said axis equal to the distance therefrom of the container edge on which the rolled edge is to be formed; movable hollow support means coaxial with said part and defining a space with the rear portion of said part; a plurality of jaws mounted on said support means, radially movable in said space, in contact with said central part and said support means, and projecting radially and forward of the perimeter of said central part, said jaws being provided facing said part and on their forwardly projecting portion with an arcuate groove of semicircular section which, when said jaws are in their retracted position, forms with said throat a rolling die of three-quarter torus shape open 40 toward said container; means for applying said jaws against said support means under slight pressure; means for applying said central part against said jaws under slight pressure; means for displacing said support means axially toward said container whereby to roll down the edge thereof in said die outwardly of the container and move said support means away from the container after formation of the rolled edge; means for displacing said jaws radially between said support means and said central part on completion of the rolled edge whereby to open 50 said die; means for reclosing said jaws when said support means has moved away from the container formed with its rolled edge; and control means of said two displacing means.

2. An apparatus according to claim 1, wherein said 60 central part is frusto-conical and has the surface of its smaller face facing the container, said throat being formed over its frusto-conical surface adjacent its larger base, the forward-projecting portions of the jaws each having a forwardly tapering frusto-conical face which 65 jointly surround said frusto-conical surface, and said groove being formed on each of said frusto-conical jaw faces adjacent its larger base.

3. An apparatus according to claim 1, wherein said central part and said jaws are made of anti-friction 70 material.

4. Apparatus according to claim 3, wherein said anti-friction material is a synthetic resin of the polytetra-chloroethylene class.

5. Apparatus according to claim 1, wherein the means 75 for displacing the jaws radially include a multiple wedge

which is in contact with said jaws and slides axially through said hollow support means.

6. An apparatus for forming a rolled edge on a container in sheet material having a shape of revolution and mounted on a fixed support, comprising, in combination, a hollow tool shank which is coaxial with the axis of the container mounted in its fixed support and terminates in a web facing the container; a fixed tool-carrier through which said tool shank slides and projects therefrom on either side and which has formed thereon a bell-mouth encompassing said web in the inoperative position; abutment means on said tool shank positioned remotely from said web for contacting said fixed tool-carrier; a hollow frusto-conical central part positioned forward of said web in the direction of the container with its smaller base facing the same and having on its frusto-conical surface adjacent its larger base a circular throat of quarter-circle section at a distance from said axis equal to the distance therefrom of the container edge to be rolled back; a plurality of jaws mounted on said web between it and said frusto-conical central part, said jaws being accommodated in said bell-mouth in the inoperative position, being radially displaceable in contact with said central part and said web, and projecting radially and forwardly of the perimeter of said central part, each with a forwardly tapering face which jointly surround the frusto-conical surface of said central part, said face having formed thereon a circular segment shaped groove of semi-circular cross-section adjacent its larger base, said groove and said throat jointly forming when said jaws are in their retracted position an edge-rolling die of hollow three-quarter-torus shape open in the direction of the container; means for applying said jaws against said web under slight pressure; means for applying said central part against said jaws under slight pressure; an arbor slideable through said tool shank, which terminates at its front end in inclined facets in contact with said jaws and which projects rearwardly from said tool shank; means for connecting said arbor to said tool shank while enabling it to slide therethrough; reciprocating actuating means coupled to the projecting portion of said arbor whereby to consecutively control axial displacement of said tool shank toward the container whereby to roll back the edge thereof in said die outwardly of the container, radial displacement of said jaws responsively to said inclined facets on completion of the rolled edge whereby to open said die, and recession of said support means from the

container after formation of the rolled edge; and means for reclosing said jaws after said tool shank has receded from the container formed with its rolled edge.

7. Apparatus according to claim 6, wherein said web has formed in its opposite each jaw an oblong opening and wherein the means for applying said jaws under slight pressure against said web include, for each jaw, a screw fixed to the jaw and extending through the corresponding oblong opening, a thrust washer threaded over said screw and contacting the web face remote from the jaws, and a spring interposed between said thrust washer and the screw head.

8. Apparatus according to claim 6, wherein the means for applying said central part under slight pressure against said jaws comprise a screw which is fixed into the arbor end formed with inclined facets and which projects from said central part, a thrust washer threaded over this screw and contacting the forward face of said central part, and a spring interposed between this thrust washer and the head of said screw.

9. Apparatus according to claim 6, wherein said arbor has an opening formed through its portion contained within said tool shank and wherein the means for connecting this arbor to the tool shank include a pin rigid with the shank and extending through said opening, means for directly connecting the projecting portion of said arbor to said reciprocating actuating means, and a spring interposed between said tool shank and said connecting means of strength sufficient to transmit the force required to roll back the edge of the container.

10. Apparatus according to claim 6, wherein the rim of said bell-mouth is chamfered internally, said jaws having formed along their perimeters a matching external chamfer adapted to engage with said internal bell-mouth chamfer whereby to reclose said jaws when said tool shank recedes from the container formed with its rolled edge.
